UNITED STATES PATENT OFFICE.

OTTO T. DEHLE, OF BOSTON, MASSACHUSETTS.

APPARATUS FOR DYEING SKEINS.

Application filed July 6, 1926. Serial No. 120,852.

This invention relates to apparatus for dyeing skeins of fibrous material, and particularly silk; and it has for its object the effecting of perfected means for revolving the skeins in the dye liquid, and for the support thereof; for elevating the skeins out from the dye, and for giving them a slow rotation above the liquid while dripping; for transferring them bodily to the washing 10 vat and revolving them therein, and for elevating them out from the washing vat.

In the drawings forming part of this specification, Fig. 1 is an end elevation, partially in section, of dyeing apparatus embodying my improvements. Fig. 2 is a side view of the same. Fig. 3 is a sectional detail view of part of the friction brake. Fig. 4 is a perspective view of the same together with other operative parts. Fig. 5 is a sectional elevation showing the operative mechanism of the skein-carrying shaft. Fig. 6 is a sectional plan view of the same. Figs. 7, 8, 9 and 10 illustrate structural details of the skein-carrying clips and the manner of mounting them on the spider.

The reference numeral 1 designates the vat for containing the dye, and 2 the washing vat beside it; 3 is a shaft provided with spiders 4 between which the skeins are suspended, and which is designed to be bodily transferred from vat to vat, and 5 are the circular bearing boxes for the ends of the shaft. These boxes fit loosely within a recess 6 in vertically slideable blocks 7. Each block is movable in ways composed of channels 9 of some non-corrosive metal and attached to the interior of the ends of the vats. Attached near to one end of the shaft 3 is a spur gear 10 designed to be held in mesh with a pinion 11 by gravity, and to be rotated thereby. This pinion in each vat is mounted on a spindle 12 passing through suitable packing boxes to the exterior of the vat where it is provided with some form of driving mechanism, preferably a sprocket wheel 13 and chain 14.

After the shaft has rotated sufficiently long for the suitably dyeing of its associated skeins, the blocks 7 at the ends of the vat 1 are drawn upward until the spur gear 10 reaches a pinion 15 power-driven and located at a level to bring the skeins on the spiders 4 entirely out of the dye-liquid. The shaft 3 being held at the level of the axis of the pinion 15 for a short time and with the gear 10 in mesh with the latter, the skeins are slowly

revolved while they are dripping free of the surplus liquid.

This being done, the blocks 7 are elevated until their recesses 6 have their bottom edges flush with the track-rails 16, and their bearing boxes 5 can be rolled out from these recesses and upon the track-rails, and thence along the latter until they enter the recesses 6 of blocks 7 above the vat 2. The latter blocks being slowly lowered until the gears 10 are in mesh with the pinions 11 of the vat 2 power driven in the same manner as are the pinions first described. This vat 2 is supplied with water for the purpose of washing from the skeins all surplus dye. After this, the shaft is raised to a suitable level to bring the skeins out of the water and to permit convenient access on the part of the attendants for the removal of the silk. Then the shaft is rolled back into the control of the blocks 7 over the vat 1; undyed skeins attached to the spiders 4, and the whole lowered into the dye-liquid for another beginning of the process.

The preferred mechanism for thus accomplishing these results is constructed as follows. Each block 7 is suspended from a chain or wire cable 20 wound upon a drum 21 which is mounted on a shaft 22, each shaft carrying the two drums associated with one vat, and being rotated through the agency of a worm-wheel 23, a worm 24 mounted on a short shaft 25, and an electric motor 26. The short shafts 25 are connected with the motor through flexible couplings 28 to permit the worms 24 to be raised out of mesh with the worm-wheels 23.

When the worm 24 is in mesh with its worm-gear 23 for the elevation of a shaft 3 and its skeins, and the motor 26 is made to turn in the proper direction, one of the blocks 7 when it reaches the proper height, will come against a movable stop 27 (Fig. 2) which is connected with a lever 29 and, by means of a rod 30, with a lever 31 which supports the free end of a short shaft 25, and thereby pushes the worm 24 up out of mesh with its worm-gear 23. At the same time it presses a friction pad 32 firmly against the periphery of a friction drum 33 fixed on the shaft 22, and thereby holds the latter from being turned by the weight of the shaft 3 and skeins.

The lever 29 sharing in this movement 110 and being automatically locked in this position by the detent 34, the shaft 3 and skeins

are thereby held at this height. For the slow rotation of the skeins while dripping, the lever 29 is shifted before the stop 27 is reached by a block 7 and at a level to hold 5 the gear 10 in mesh with the driving pinion 15; but this dripping having stopped, the worm 24 is lowered into mesh with its worm-gear 23 and the blocks 7 raised until stopped in the manner above described.

10 As the shaft 3 is thus brought up to the desired level, it comes between the ends of the two bifurcated levers 35 which were located to receive the same. The operator then 15 presses the lever inward further, compressing the spring 36 of the friction pad 32 and carrying the worm 24 up into mesh with a worm-gear 37 which turns with a crank 38; the latter being connected by a pitman 40 to the levers 35, and the parts so proportioned 20 that one limit of their swing is over the center of one vat, and the other limit over the center of the other vat. Hence, when the shaft 3 is thus delivered into the control of the levers 35 and the worm 24 put into mesh 25 with the worm-gear 37, the shaft and skeins are at once urged along the rails 16 to the recessed blocks 7 of the other vat. At this point, the levers are stopped by the operator's depressing the worm 24 out of mesh 30 with the worm-gear 27, but not into mesh with the worm-gear 23.

The brake lever 29^a having previously been locked to hold its brake-pad 32^a tightly against the friction drum 33^a, it is gradually released to permit the shaft 3 and its contents to be lowered into the water in the vat 2. Here its spur gear 10 descends into mesh with the power-driven pinion 15 and the skeins are slowly revolved in the water 40 until suitably washed.

When this is accomplished, the worm 24^a is lowered into mesh with the worm-gear 23^a and the drums 21^a are made to wind up the cables 20^a and elevate the blocks 7^a to a 45 height suitable for the removal of the washed skeins from the spiders 4. After this, the shaft and spiders are returned across the rails 16 to the other side; a fresh supply of skeins suspended from the spiders, and 50 the whole lowered in the same manner as before down into the dye-liquid.

The construction of the spring pads 32 is shown in detail in Fig. 3, wherein it is seen that the lever-arm 41 slidably supports the 55 pad, and by means of the spring 36 permits a considerable range of movement of the lever-arm while maintaining continuous braking action.

The preferred means for supporting the 60 skeins consist of the spiders 4 provided near their peripheries with numerous clips 50 each of which comprises a main body 51 to which the clip 50 is hinged at 52, and which is slidably supported by slender rods or pins 53 65 slidably held by the spider and resiliently

held by springs 54 mounted on the pins. Each clip 50 is formed with several teeth 55 having rounded ends adapted to enter seats 56 in the body 51, and is locked in its closed position by a spring latch 57. The pins 53 and springs 54 are supported in hollow bosses 59 formed on the spiders, these bosses being disposed in a zig-zag arrangement, as shown in Fig. 10, so that each clip when opened will rest upon the end of a 70 body 51 of the adjacent device, and thereby be in a convenient position for the skein to be attached thereto.

In attaching the end of a skein to one of these clips 50 the threads or yarns of the 80 skein are somewhat evenly distributed about the teeth 55 for the purpose of enabling the dye liquid to more freely penetrate the skeins and thereby to dye the same more uniformly.

The clips 50 are preferably perforated and 85 notched, as indicated in Fig. 7 in order to permit the dye to more readily reach the portions of the skeins held by the teeth 55 and by the clips themselves.

After the skeins have been dyed and 90 washed, they are readily removed from the clips by swinging the latter one by one down to a substantially horizontal position and raising therefrom the skein.

What I claim as my invention is:

1. In a machine for dyeing skeins, two closely disposed parallel vats, a shaft adapted 100 for carrying skeins, continuously rotating mechanism in each vat adapted to rotate said shaft when lowered therein, means for raising and lowering said shaft out from and down into each vat, and means for horizontally moving said shaft from a point above one vat to a point above the other vat and for keeping it parallel with the vats during 105 its removal.

2. In a machine for dyeing skeins, two closely disposed parallel vats, a shaft adapted 110 for carrying skeins, continuously rotating mechanism in each vat adapted to rotate said shaft when lowered therein, means for raising and lowering said shaft out of and down into each vat, and means including track rails for horizontally moving said shaft from a point above one vat to a point above the other vat. 115

3. A machine for dyeing skeins of silk and the like, comprising two tanks, one for a dye liquid and the other for a washing liquid, 120 a shaft adapted for supporting the skeins, means in each tank for rotating said shafts, means for moving said shaft up from and down into the tanks, track rails upon which said shaft can be removed from one tank to the other, and swinging arms adapted to be engaged with said shaft for moving it along said rails.

4. A machine for dyeing skeins of silk and the like, comprising two tanks, one for a dye liquid and the other for a washing liquid, a 130

shaft for supporting the skeins, means in each tank for rotating said shaft, a circular bearing box for each end of said shaft, means for raising said shaft up from and lowering it down into the tanks, and track rails upon which said boxes can roll for the transference of said shaft from one tank to the other.

5. A machine for dyeing skeins of silk and the like, comprising two tanks, one for a dye liquid and the other for a washing liquid, a shaft adapted for supporting the skeins, means in each tank for rotating said shaft, circular bearing boxes for the ends 10 of said shaft, means for raising said shaft up from and lowering it down into the shafts, track rails along which said boxes can roll, and swinging arms adapted for engaging said shaft for moving it along 15 said rails.

6. A machine for dyeing skeins of silk and the like, comprising a tank, vertical ways at each end thereof, blocks slideable in 20 said ways, each block having a recess in its edge, a circular bearing box loose in each recess, a shaft having its ends rotatably supported in said boxes, means for raising and lowering said blocks, and track rails upon 25 which said boxes can be rolled when the blocks are elevated to the proper height.

7. A machine for dyeing skeins of silk and the like, comprising two tanks, each having vertical ways at each end thereof, blocks slideable in said ways, each block 30 having a recess opening toward the opposite tank, circular bearing boxes loose in said recesses of one tank, a shaft terminally and rotatably supported by said boxes, horizontal track rails uniting the upper ends 35 of the ways of one tank with the ways of the other, and means for rolling said boxes and shaft along said rails.

8. A machine for dyeing skeins of silk and the like, comprising a tank, vertical 40 ways at each end thereof, a power driven pinion at the lower end of one of said ways, a power driven pinion near the upper end thereof, a shaft, means for raising and lowering said shaft in said ways, and a spur gear on said shaft for engaging with said pinions when at the proper height.

9. A machine for dyeing skeins of silk and the like, comprising two tanks, vertical ways at each end of each tank, a shaft 45 adapted for supporting skeins of silk and the like, bearings for the ends of said shaft fitted to the ways of each tank, means for raising and lowering said ways in either tank, track rails joining the upper ends of the ways of one tank with the ways of the other tank, means for automatically stopping the elevation of said bearings at the level of said rails, and means for receiving said shaft and for moving it along said rails 50 from one tank to the other.

10. A machine for dyeing skeins of silk and the like as set forth in claim 9, in which the last-named means consist of instrumentalities each having two spaced projections up between which an end of said 70 shaft rises and by means of which it is moved from end to end of the track rails.

11. A machine as set forth in claim 9, in which the last named means consists of united swinging arms each having two 75 spaced projections between which an end of the shaft rises and by which it is moved along said rails.

12. A machine for dyeing skeins of silk and the like, comprising a tank, vertical 80 ways at its ends, blocks slidably carried in said ways, a shaft adapted for supporting skeins having its ends supported in said blocks, a shaft supported above said tank having drums, flexible connections between 85 said blocks and drums, power operated means for rotating said drums, and means actuated by said blocks when elevated to a predetermined level for disconnecting the power operated means from said drums. 90

13. A machine for dyeing skeins of silk and the like, comprising a tank, vertical ways at its ends, blocks slidably carried in said ways, a shaft adapted for supporting skeins having its ends rotatable in said 95 blocks, a shaft supported above said tank having two drums and a worm gear, flexible connections between said blocks and drums, a power actuated worm adapted to be put into mesh with said worm gear, a brake for 100 the upper shaft, and means operated by the elevation of one of said blocks to a predetermined height for unmeshing said worm and gear and for applying said brake.

14. A machine for dyeing skeins of silk 105 and the like, comprising two tanks, vertical ways at the ends of each tank, blocks slideable in said ways, a shaft rotatably but removably carried by the blocks in either tank, a shaft located above each tank provided with a drum and a worm gear, flexible connections between said blocks and drums, a worm gear located above one of said worm gears but spaced therefrom, means operated by said elevated worm gear for transferring 110 said shaft from one set of ways to the other when its blocks have been elevated to a predetermined height, and a power driven worm located between said spaced gears adapted to be put into mesh with either. 115

15. A machine as set forth in claim 14 having a brake for the lower of the worm gears resiliently supported, and a hand lever controlling both the brake and the shifting of the worm. 120

In testimony that I claim the foregoing invention, I have hereunto set my hand this 21st day of June, 1926.
